SOFA BED LOCK

Adrian De Bruin, Kenosha, Wis., assignor to Simmons Company, Kenosha, Wis.

Application November 26, 1954, Serial No. 471,466

3 Claims. (Cl. 5—13)

This invention relates to sofa beds of the type having a bed bottom comprising a plurality of hingedly connected sections which are folded into a sofa frame to form a seat. The invention is particularly concerned with means for guiding the bed bottom when folded into a predetermined position in or on said frame, and for preventing sideward movement of the folded bed bottom when it is disposed in seat position.

Sofa beds are quite bulky, and in shipment are quite often stood on end to facilitate car loading. The foldable bed bottom frame, together with the mattress which it carries, constitutes a large part of the very substantial weight of a sofa bed, and while in the usual sofa bed, the means provided for movably mounting the bed bottom in the sofa frame is more than adequate to support the bed bottom in all usual positions, such support means are not designed to carry the full weight of the bed bottom and mattress when the sofa is stood on end. As a result, the standing of sofa beds on end for shipment, and the shocks to which the sofa bed mechanisms are subjected in shipment, have at times caused damage to the bed bottom suspension mechanism, resulting occasionally in malfunctioning of the bed bottom mechanism or sufficient misalignment of the parts to cause undue wear of the upholstery on one arm or other of the sofa bed by the movement of the bed bottom into and out of the sofa frame during normal usage.

Accordingly, it is the object of the present invention to provide simple and economical means for securing the folded bed bottom within the sofa frame, and particularly for preventing sideward movement of the sofa frame when in seat position. Other objects and advantages will become apparent as the invention is explained with reference to the following drawing, in which:

Figure 1 is a side elevation of only the essential parts of a sofa bed, showing the bed bottom in a partially folded condition just prior to its final folding movement into seat position on the sofa frame. Certain portions of the structure have been broken away to better illustrate the elements of particular importance to the invention;

Figure 2 is a side elevation similar to Figure 1, but showing in progress the final folding movement of the bed bottom into seat position on the sofa frame;

Figure 3 is a side elevation similar to Figures 1 and 2 but showing the bed bottom fully folded into seat position on the sofa frame. As in the case of Figure 1, portions of the structure are broken away to better illustrate the pertinent details;

Figure 4 is an enlarged fragmentary perspective view of a rear lower corner of the stationary sofa frame, and the adjacent corner of the folded bed bottom, showing the locking interengagement of their respective parts for resisting sidewise movement of the bed bottom;

Figure 5 is a perspective view showing the inside of the front boards of the bed bottom and stationary frame respectively, just prior to movement of the bed bottom into final seat position, and illustrating in greater detail

2

the interengagement of the locking members which prevent relative sideward movement of the bed bottom and frame at the front of the sofa;

Figure 6 is a perspective view similar to Figure 4, but showing from the back of the sofa a modified form of the arrangement of Figure 4;

Figure 7 is a sectional view taken along the line 7—7 of Figure 6.

Briefly, a sofa bed in accordance with the invention is one in which the foldable bed bottom is swingable into and out of seat-forming position on the sofa frame and in which there are provided suitable inter-engaging guide means or abutments on the bed bottom and on the sofa frame for guiding the bed bottom into a predetermined position laterally of the sofa frame, and restraining it in that position against whatever sideward forces might be exerted upon it in normal handling and use of a sofa bed.

As shown in the accompanying drawings, referring particularly to Figures 1, 2 and 3, the sofa bed includes a normally stationary sofa frame 10 including the usual upholstered arms with their supporting legs, and an upholstered back rest. These usual members are shown only in dotted outlines which indicate generally their placement on a skeletal metal frame which is the basis of the stationary sofa member.

The skeletal frame is preferably of angle iron construction and includes a pair of side panels 12, each having a rear post 14 and a shorter front post 16 connected by a lower cross member 18 to which both posts are further secured by means of corner braces 20. The two side panels are connected together at their front ends by a fixed front board 22 to which they are bolted and which also serves to partly conceal the bed bottom frame when the latter is folded into seat position (Fig. 3).

The side panels are also connected together at their rear corners by upper and lower cross members 24 and 26 which, like the structural members of the side frames, are preferably formed of angle iron. The side panels are braced at their lower corners to the lower cross member 26 by means of suitable corner braces 28, the form of which, in the embodiment of Figures 1 to 4 inclusive, enters into the invention, as will subsequently be described.

Also extending between the two side panels of the skeletal sofa frame is a back rest panel 30 which carries the upholstery of the back rest. It is secured to the rear post members 14 of the side panels by means of upper and lower braces 32 and 34, the lower brace 34 also serving as a point of attachment for part of the bed bottom mounting means.

The bed bottom comprises four hingedly connected sections, viz, a head section 36, an intermediate section 38, a connecting section 40, and a seat section 42, all of which may be disposed in co-planar alignment to form a bed. The bed bottom and its supporting mechanism as herein illustrated, are shown in all essential elements in U. S. Patent No. 2,595,038, issued to Edward E. Woller, and in U. S. Patent No. 2,749,559, issued to John S. Petersen, both owned by the assignee of this invention. The foregoing patents contain a detailed description of the bed bottom and its several appurtenances, which will be repeated here only to the extent necessary to a clear understanding of the present invention.

The inner or head section 36 of the bed bottom is connected to the sofa frame by means of a pair of links 44 and 46 which determine for it a fixed path of movement from the intermediate position of Figure 1, to the fully-folded, seat position of Figure 3. The intermediate section 38 is supported and guided in this movement by its hinged connection to the inner or head section 36, and by a support arm or link 48 which is pivoted at

one end to a bracket 50 on the sofa frame, and at its other end to a bracket 52 secured to the intermediate section. By comparing Figures 3, 2 and 1, in that order, it will be observed that path of movement determined by links 44, 46 and 48 is such that in the final movement of the folded bed bottom into seat position, the lower rear edge of the folded bed bottom moves essentially rearwardly, whereas the forward end of the folded bed bottom moves essentially downwardly. The movement of the bed bottom into seat position is cushioned by tension springs 49 stretched between bracket 52 and the upper end of the front post 16.

In the bed position (not shown), the bed bottom is supported by the links 44, 46 and 48 which connect it to the sofa frame, and also by two foldable legs 54 and 56 at each side of the bed bottom, the leg 54 being pivoted to the intermediate section 38, and the other leg 56 to the outer section 42, which, referring to Figure 3, ultimately becomes the cushion-supporting or seat section of the sofa bed.

Also connected to the seat section 42 adjacent the connecting section 40 is a movable front board 58 which is disposed beneath the bed bottom at some distance when the latter is in bed position, but which assumes a position in front of and generally paralleling the connecting section 40 when the seat section 42 is folded into superposed relation to the intermediate section 38, as shown in Figures 1 to 3. The linkage for accomplishing this movement, as well as the folding and unfolding of the support legs, includes the links 60, 62 and 64. Also shown in the drawings but not here described in detail, is a locking mechanism which includes the links 66, 68 and 70. These linkages, being disclosed in the patents previously referred to, are not here again described, being no part of the present invention.

The links 64 and 70 are actuated by the movement of the inner section 36 relative to the intermediate section 38, being pivoted to an angle bracket 72 secured to the inner or head section 36 at a point spaced well below the pivotal connection between the two sections 36 and 38, as seen in Figure 1. The angle bracket 72 and the corner brace 28 between the side panel 12 and the lower rear cross member 26 of the stationary frame are specially formed to achieve the purpose of the invention (see Fig. 4).

The bracket 72 is formed of a short section of angle iron, one leg of which is placed back-to-back with the bottom flange of the side rail of the head section 36 and permanently secured thereto as by riveting or the like. The other flange of the bracket 72 is offset sidewardly from vertical flanges of the side rail of the head section 36 to provide clearance between the side rail and the link 70 for the passage of the head of the hinge rivet 74 between the head and intermediate sections. The vertical flange of the angle bracket 72 thus extends downwardly in the bed position, and rearwardly in the seat position, constituting a tongue extending in the direction of movement of the inner portion of the bed bottom as it swings rearwardly into seat-forming position.

The corner brace 28 is similarly formed of angle iron with one flange disposed in a vertical plane and the other extending toward the front of the sofa bed. The forwardly extending flange is provided with a notch 76 aligned with the rearwardly-extending flange or tongue of the angle bracket 72, and encompasses that tongue as shown in Figs. 3 and 4 when the bed bottom is in seat position.

A single lock is provided for the front end of the folded bed bottom and is disposed preferably midway along the frontboards 22 and 58 which extend between the sofa arms to conceal the folded bed bottom in seat position. The front lock comprises an angle bracket 78 secured to the lower or fixed front board 22 with both of its flanges disposed vertically (see Figs. 1, 3 and 5), the rearwardly extending flange being provided in its

upper edge with a flared notch 80. The upper or movable front board 58 which is secured to the bed bottom is provided with a mating tongue 82, the engaging portion of which is offset rearwardly in alignment with the notch 80 of the angle bracket 78. The engaging portion of the tongue 82 is also provided with a flared central notch 84 which, when the bed bottom is fully disposed in seat position, mates with the rearwardly extending flange of the corner bracket 78 and effectively prevents sideward movement of the movable front board 58. The flared notch 80 in the upper edge of the rearwardly extending flange of the angle bracket 78 serves to bring the two front boards into front-to-rear alignment to assure the smooth appearance of the front of the sofa bed when disposed as a sofa.

It will be observed that the direction of engagement of the interengaging members 72 and 28 of the rear locks is primarily horizontal, and that of the interengaging members 78 and 82 the front lock primarily vertical, following the general path of movement of the adjacent parts of the bed bottom, as determined by the pair of links 44 and 46 connecting the stationary frame 10 with the head section 36, and the arm 48 connecting the frame with the intermediate section.

In Figures 6 and 7, there is illustrated a modification of rear corner lock which may be used where it is not advantageous to utilize one of the structural elements of the stationary frame. In the modified form of Fig. 6, the rear corner lock includes an angle bracket 86 having one flange disposed in a vertical plane and riveted to the rear cross member 26 of the sofa frame, and the other flange extending forwardly in a horizontal plane and provided with a flared notch 88 for receiving the rearwardly extending tongue of the angle bracket 72 secured to the head section 36 of the bottom. In either embodiment, any side thrust exerted on the folded bottom, as, for example, by its own weight and the weight of the mattress if the sofa bed should be upended, is sustained by the stationary frame 10 with practically no side movement of the bed bottom.

By means of the foregoing arrangements, in which side thrust exerted on the bed bottom when folded in seat position is transmitted directly to the frame, the supporting links and arms 44, 46 and 48 which guide and support the bed bottom in this movement can be efficiently and safely designed for loads exerted principally in vertical planes. This is particularly important in those cases, for example, where the distance between the arms of the sofa bed is substantially greater than the width of the bed bottom frame, and in which, heretofore, any side thrust exerted on or by the bed bottom was transferred to the stationary frame through the supporting links, and from the movable front board directly to the upholstered sofa arms.

The features of the invention believed to be new and patentable are set forth in the appended claims.

I claim:

1. In a sofa bed, a sofa frame, a bed bottom comprising a plurality of hingedly connected sections which are foldable from bed position in which said sections extend forwardly of said sofa frame to a seat position on said sofa frame, mounting means swingably connecting said bed bottom to said sofa frame for carrying said bed bottom into seat position on said sofa frame, through a fixed path of movement in which the rear portion of the bed bottom moves rearwardly into seat position and the forward portion moves downwardly into seat position, separate interengageable guide and lock means on said frame and rear portion respectively and on said frame and forward portion of said bed bottom respectively, for guiding said bed bottom into, and locking said bed bottom in, a predetermined position sidewardly of said sofa frame when said bed bottom moves into seat position.

2. In a sofa bed, a sofa frame, a bed bottom comprising a plurality of hingedly connected sections foldable from

bed position in which said sections extend forwardly from said sofa frame to a position in which said sections are folded and stowed on said sofa frame to form a seat, said sections including an innermost section pivotally connected to said sofa frame for movement through a fixed path from and to a vertical position at the rear of said frame, and an intermediate section pivoted to said innermost section and to a link which is also pivoted to said frame whereby said intermediate section is movable through a fixed path from and to horizontal position extending forwardly from the lower end of said innermost section when in seat position, the lower end of said innermost section moving rearwardly into seat position, the forward end of said intermediate section moving downwardly into said seat position, interengaging means on said frame and said lower end of the innermost section respectively, and other interengaging means connected to the forward end of said intermediate section and to said frame respectively, for preventing sideward movement of said bed bottom when disposed in seat position.

3. In a sofa bed, a sofa frame having side arms, a bed bottom comprising a plurality of hingedly connected sections foldable from bed position in which said sections extend forwardly from said sofa frame to a position in which said sections are folded and stowed in said sofa

25

frame to form a seat, said sections including an innermost section pivotally connected to said sofa frame for movement through a fixed path from and to a vertical position at the rear of said sofa frame, and an intermediate section 5 pivoted to said innermost section and to a link which is also pivoted to said sofa frame whereby said intermediate section is movable through fixed path from and to horizontal position extending forwardly from the lower end of said innermost section when in seat position, the lower end of said innermost section moving rearwardly into seat position, the forward end of said intermediate section moving downwardly into seat position, a front board carried by said bed bottom and disposed forwardly of said intermediate section in seat position, said front board in 10 seat position extending between said side arms for concealing said bed bottom, interengaging means on said sofa frame and on one of said innermost or intermediate sections adjacent the hinged connection therebetween, for preventing sideward movement of said bed.
